G. E. THACKRAY.

COKE OVEN.

APPLICATION FILED SEPT. 2, 1916.

1,211,503.

Patented Jan. 9, 1917.

WITNESS

INVENTOR

Emmer Leavay.

Geo. E. Thackray

UNITED STATES PATENT OFFICE.

GEOEGE E. THACKRAY, OF WESTMONT BOROUGH, PENNSYLVANIA.

COKE-OVEN.

1,211,503.

Specification of Letters Patent.

Patented Jan. 9, 1917.

Original application filed October 28, 1913, Serial No. 797,701. Divided and this application filed September 2, 1916. Serial No. 112,204.

To all whom it may concern:

Be it known that I, GEORGE E. THACKRAY, a citizen of the United States, residing in Westmont borough, in the county of Cambria and State of Pennsylvania, have invented certain new and useful Improvements in Coke-Ovens; and I do hereby declare the following to be a full, clear, and exact description of the invention, such as will enable others skilled in the art to which it appertains to make and use the same.

This invention is a division from my application filed October 28, 1913, Serial No. 797,701.

My invention relates to coke oven construction and more especially to that class of coke ovens having long horizontal retort coking, or distilling chambers, with heating-flues in the side walls thereof, certain of the objects of my invention being the manner of constructing expansion joints at the tops and bottoms of the walls of the retort whereby they may expand or contract without injurious effects.

A further object of my invention relates to the gas burners which are disposed in such a manner that the nozzles are easy of access for inspection or cleaning from the top of the battery, in case they become clogged with dust or fused particles. These gas burners may be made small so they may be removed through the flues from the top of the battery and others inserted, or they may be formed in the base blocks of the heating flues. In case the gas distribution pipes are arranged side by side horizontally, a recess is formed on the under side of the base block wide enough to extend over the ports of both distribution pipes, and this formation of the burners in the base blocks of the heating flues with a recess wide enough to extend over the ports in both distribution pipes forms another feature of my invention.

Another object of my invention is to gradually decrease the size of the air inlet ports from the ends of the oven to the center whereby a more uniform heat is imparted to the oven, as I have discovered

that the exposed ends of the ovens, which are subject to outside cooling influences, will require more gas than the center of the oven. As the inlet air ports decrease in size, I may also enlarge the size of each of the heating flues, although I may construct the heating flues of the same size the entire length of the oven.

My invention also consists in the novel constructions, arrangement and combination of parts, substantially as hereinafter described and pointed out in the appended claims.

Having given a general description of my invention, I will now, in order to make it more clear, refer to the accompanying sheet of drawings forming part of this specification and in which:

Figure 1 is a vertical section longitudinally of the ovens, showing the form of burners and distribution pipes. These distribution pipes are arranged one above the other, the section being taken on the line I—I of Fig. 2, showing the distribution pipes in section; Fig. 2 is a vertical section transversely of the ovens, taken on the line II—II of Fig. 1; Fig. 3 is a vertical section taken on the same line as Fig. 2, but showing the distribution pipes arranged side by side horizontally with a recess formed in the under faces of the burner blocks wide enough to extend over the ports or openings of both distribution pipes; Fig. 4 is a vertical section taken longitudinally of the oven on the line IV—IV of Fig. 3, showing a portion of the end of the shorter outer distribution pipe in section and a part of the longer one, which extends to the intermediate set of heating flues in elevation; Fig. 5 is a detail section, transversely of the ovens, showing a removable burner or nozzle with the distribution pipes arranged side by side as in Fig. 3; Fig. 6 is a vertical transverse sectional elevation of the lower portion of the retort oven and surrounding parts of modified form similar to section of Fig. 2, to show the manner of forming expansion joints at the bases of the retort ovens; Fig. 7 is a vertical sectional elevation longitu-

dinarily of the ovens, showing the upper portion of the heating flues, to illustrate the details of the portion, and the expansion joints at the top of the heating flues.

5 Referring now to the numerals of reference on the drawings:—1 represents each of the end regenerators, which are below the coking chambers. The interior regenerators 2 are each of greater length and area than the end regenerators 1; 3 indicates the regenerator ports connecting the tops of the outer regenerators 1, and 4 are similar ports for the regenerators 2. These ports 3 and 4 are connected with the lower longitudinal oven flues 5 which are divided at 30, Fig. 1, into lengths corresponding to those of the regenerators located beneath them and the retort ovens 6. The lower oven flues 5 communicate with the heating flues 7 by means of horizontal ports 8 on both sides thereof, which ports preferably decrease in size from the ends of the oven toward the center.

Referring now to Figs. 1, 2, 3 and 4:—gas 25 is received by the distribution pipes 9 and 10 from the supply pipes 11 and 12. These distribution pipes 9 and 10 are constructed of refractory material formed in sections with their ends rubbed together and provided with holes 13 for admitting the gas to the burners or nozzle bricks 14 which, in this case, are constructed in the base blocks 15 of the heating flues 7, as shown.

The distribution pipe sections are preferably of rectangular outline in cross section and are either built in the wall horizontally, one above the other, as illustrated in Figs. 1 and 2, or side by side, as shown in Figs. 3 and 4, and in the latter case I prefer to form a recess 16 on the under face of the base block 15, wide enough to extend over the holes 13 in either of the pipes 9 or 10. With this construction the base blocks 17 may be modified by forming them with inclined edges to rest on correspondingly inclined sides of the wall, as shown in Figs. 2 and 3.

Referring now more especially to Figs. 5, 6 and 7 of the drawings, the supply of gas 50 which is burned in the heating flues, enters the battery by means of the distribution pipes 18 and 19, the pipes 18 being shorter than the pipes 19 and located above the same, as shown in Figs. 6 and 7, or side by side, as shown in Fig. 5, both pipes being embedded in the masonry construction below each row of heating flues 7. Below each individual flue 7 is an opening 20 in the distribution pipes 18 or 19, as the case 55 may be, directing the gas to the nozzles or burners 21, which are seated in the floor walls of the heating flues 7.

The ports 8 admit air into the heating flues 7 just above the burners 21 at either

side thereof, where it mixes with the combustible gases which then burn and flow upwardly in the heating flues, thereby heating the ovens, thence through the upper openings 22 which are each controlled by a damper 23 and thence into the top horizontal 65 canals 24.

An expansion joint 25 is formed at the top of the division walls of the heating flues, as clearly shown in Fig. 7 and at the base of the retort oven 6, as shown at 26 in Fig. 3. This expansion joint 25 is made by fitting blocks 17 of refractory material loosely into grooves 27 or resting their ends upon the ledges 28.

Although I have shown and described my improvements in considerable detail, I do not wish to be limited to the exact and specific details shown and described, but may use such substitutions, modifications or equivalents thereof as are embraced within the scope of my invention, or as pointed out in the claims.

Having thus described my invention, what I claim and desire to secure by Letters Patent is:—

1. In a retort coke oven having vertical side walls provided with a plurality of vertical heating flues, a base block at the lower end of each heating flue, a burner formed in said base block, and distributing pipes of different lengths beneath and connecting with the base blocks.

2. In a retort coke oven having vertical side walls provided with a plurality of vertical heating flues, a base block at the lower end of each heating flue upon which the vertical side walls rest, a burner formed in said base block, distribution pipes of different lengths beneath the base blocks, a plurality of holes in each distribution pipe for supplying gas to the burners, and a recess formed beneath the burners on the under side of each base block wide enough to cover the holes in either of a pair of distribution pipes.

3. In a retort coke oven having vertical side walls provided with a plurality of vertical heating flues, a base block at the lower end of each heating flue upon which the vertical side walls rest, a burner formed in said base block, distribution pipes of different lengths beneath the base blocks, a plurality of holes in each distribution pipe for supplying gas to the burners, a recess beneath the burners formed on the under side of each base block wide enough to cover the holes in a plurality of distribution pipes, and horizontal ports decreasing in size from the ends of the oven for admitting air to the vertical heating flues above the burners through the opposite side walls.

4. In a retort coke oven an oven floor formed of blocks of refractory material, the

ends of which adjacent the side walls are separated therefrom to form expansion joints, a plurality of vertical heating flues, the upper portions of the walls of which are spaced apart forming upper expansion joints, a base block at the lower end of each heating flue, a burner formed in said base block and distribution pipes of different lengths beneath and connecting with the base blocks.

In testimony whereof I hereunto affix my signature.

GEORGE E. THACKRAY.
